[57] CLAIM

The ornamental design for an automatic silverware roller, as shown and described.

DESCRIPTION

FIG. 1 is a diagrammatic perspective view of the automatic silverware roller in full lines with silverware and napkins shown in broken lines representing environmental association matter being for illustrative purposes only and forming no part of the claimed invention;

FIG. 2 is a left side elevational view thereof;

FIG. 3 is a right side elevational view thereof;

FIG. 4 is a front elevational view of the automatic silverware roller;

FIG. 5 is a rear elevational view thereof;

FIG. 6 is a top plan view thereof; and,

FIG. 7 is a bottom plan view thereof.
